Primary Examiner — Michelle E. Wilson*Assistant Examiner* — Caitlin A Laverty(74) *Attorney, Agent, or Firm* — Jeffer Mangels Butler & Mitchell LLP; Brennan C. Swain, Esq.**CLAIM**

The ornamental design for a holster, as shown and described.

DESCRIPTION

FIG. 1 is a perspective view of the holster;
 FIG. 2 is a front view of the holster;

FIG. 3 is a back view of the holster;

FIG. 4 is a right side view of the holster;

FIG. 5 is a left side view of the holster;

FIG. 6 is a top view of the holster; and,

FIG. 7 is a bottom view of the holster.

In the drawings, the broken lines show portions of a holster that form no part of the claim.

1 Claim, 5 Drawing Sheets(56)
